UNITED STATES PATENT OFFICE.

ALFRED JAMES JUNG, OF KENSINGTON WEST, LONDON, ENGLAND.

TICKET PRINTING AND ISSUING MACHINE.

1,090,543.

Specification of Letters Patent. Patented Mar. 17, 1914.

Application filed February 21, 1911. Serial No. 610,111.

To all whom it may concern:

Be it known that I, ALFRED J. JUNG, a subject of the King of Great Britain, residing at Kensington West, London, England, have invented new and useful Improvements in Ticket Printing and Issuing Machines, of which the following is a specification.

This invention relates to machines for printing and issuing, as required, tickets such as used, on steamship, airship, railway, tramway and omnibus routes, or in theaters, halls, sports grounds and other buildings or inclosures, the chief object of the invention being to provide a simple, reliable and efficient machine for this purpose.

According to the present invention a single ticket is fed into the machine, printed, numbered, dated, priced and issued conveniently by the operation of a single handle or lever, controlling the movement of a printing member which draws the ticket in automatically, passes it between its printing face and an impression member and after printing ejects the ticket, the total number of tickets printed together with the price of each ticket as issued, being automatically recorded within the machine and with the initiation of the printing movement, the parts under the direct control of the operator are automatically locked against tampering or improper movement.

A single plate or block furnished with fixed or permanent and also changeable matter or the desired particulars in the form of electro type or types and constituting a form plate or member is mounted to reciprocate or move to and fro in one plane in suitable guides under the control of the user and in moving draws the blank ticket into the machine and feeds it between its printing surface and a rubber or other suitable impression roller so that the ticket receives a print from the matter on the form plate and is then ejected.

Ink is supplied to the typographic matter on the plate each time it is moved by an ink saturated roller or rollers, conveniently two ink rollers are employed, each adapted to act upon approximately one half of the surface of the plate, thus effecting a considerable economy in the dimensions or length of the machine.

When tickets such as used on a steam or

airship, rail or tramway, or omnibus route are to be produced, the permanent particulars on the form plate which as stated is moved to and fro in one plane, comprise the names of the various stopping places or stations each station being also designated by a distinguishing letter or numeral, conveniently placed alongside of the name, for outward and return journey. The movable or changeable particulars comprise, preferably, a price printing mechanism and a station printing mechanism controllable by the operator, a dating mechanism changeable as required, together with automatically controllable price totalizer and counter, also an automatically operated mechanism for numbering the tickets as issued.

When the machine is used to print tickets for theaters, halls, or the like, sports or other inclosures, the form plate movable as above stated, bears as the permanent particulars the names of the various blocks of seats, positions or locations, each accompanied by a designating numeral or symbol when necessary and the movable or changeable particulars may be the same as already referred to in connection with railway, tramway or similar tickets.

Mechanisms are also provided in accordance with this invention for automatically locking the handles or devices which are under the direct control of the operator for setting the price and destination printing devices to prevent improper manipulation or tampering, and also to lock the operating lever against return movement until a ticket has been printed and issued and the recording devices operated.

The invention will now be described more particularly as applied to the printing and issuing of tickets such as are used on railway, tramway, omnibus or ship routes, or other tickets bearing the names of a series of stations or positions with different prices, the machine being adapted to print and issue the ticket, so that it bears upon it full particulars of the station or place for which the ticket is available, the price charged, the number of the ticket and also the date of issue, the issue of the ticket and the price printed on it being also automatically recorded within the machine outside of the control of the operator.

Referring to the accompanying draw-

ings:—Figure 1 is a sectional elevation of a preferred form of embodiment of the invention. Fig. 2 is a front sectional elevation the casing being removed. Fig. 3 is a rear sectional elevation the back of the casing being removed. Fig. 4 is a sectional side elevation showing certain details. Fig. 5 is a sectional side elevation showing other details. Fig. 6 is a detail sectional view. Fig. 7 is an outside side elevation of the machine and Fig. 8 is an outside front elevation and Fig. 9 is a view of the ticket as issued.

10 A is the plate, or printing member, B the impression member or roller, C the casing, D the operating lever, E E¹ the inking rollers, F the price setting handle, G the station or destination setting handle, H the numbering mechanism, J the dating mechanism, K the locking mechanism for handles F and G, L the locking mechanism for the lever D, M the price counter or totalizer and O the counter of tickets issued.

15 The plate A is supported on two side bars or members A¹ adapted to move in guides A² formed on side frames C. The plate has the permanent or fixed printing matter *a* conveniently in the form of an electrotype mounted upon its face and the 20 movable or changeable printing matter is conveniently borne upon disks or rollers Fig. 1 carried on the plate or by its supporting members A¹ so that the type thereon are flush with the printing surface of the electrotype *a*, the plate is reciprocated to and 25 fro in one plane under the control of the operator.

30 The movable or adjustable printing matter comprises a wheel or cylinder G¹ furnished with type numerals or it may be letters or symbols, corresponding to those on the form plate designating the various stations or stopping places. This type cylinder G¹ is under the control of the user 35 so that the particular letter or numeral can be turned around to be flush with the printing surface *a* of the form plate A to form for the time being an integral printing part thereof. For convenience in setting this 40 roller the index handle or disk G is mounted upon a shaft mounted in the frames C and having a toothed wheel g¹ gearing with a toothed wheel g² on the shaft f of the type-carrying cylinder G¹ so that by setting a particular figure opposite a stationary finger or indicator it will be insured 45 that the corresponding type on the cylinder G¹ will be printed on the ticket next issued. The type cylinder G¹ moves to and fro with 50 the plate A while the controlling handle G is mounted in the stationary frame or casting C, so that adjustments of the cylinder G¹ can be made only when the form plate A is in normal or in operative position as 55 shown in Fig. 3, as only then are the wheels

g¹ g² in mesh. A similar type cylinder F¹ furnished with the various prices that can be charged for tickets is also provided mounted upon the shaft g³. The shaft g³ on which the tubular shaft f carrying the 60 cylinder G¹ is mounted carries a pinion f¹ gearing, when the plate A is in inoperative position, with a pinion f² on the shaft of the handle F which controls the movements of the cylinder F¹ and is marked with the 65 prices chargeable. The cylinder F¹ moves to and fro with the plate A while the handle F is carried by the frame C so that the cylinder F¹ can only be adjusted when the 70 wheels f¹ f² are in mesh which is when the 75 plate is in its inoperative position as shown in Fig. 3.

The printing disks F¹ G¹ are provided with star wheels respectively f¹⁰ g¹⁰ with which engage springs f¹¹ g¹¹ to prevent the 80 wheels being rotated accidentally during the printing operation.

85 As the index disks or handles F, G are rotatable but are not movable with the form plate it is necessary in order to prevent 90 tampering or improper use to lock them against movement after the plate A has been moved through part of its travel or prevent them being operated except when the plate A is in the inoperative position 95 as shown in Fig. 3. To avoid such misuse a locking mechanism is provided, according to this invention, and is controlled by the movements of the form plate. For this purpose the gear wheels of the type cylinders 100 F¹ G¹ which mesh with gear wheels on the shafts of the index disks, are adapted to be locked against rotation when the two sets of wheels are not in mesh, by studs k k¹ or the like carried by a sliding member K which is 105 slotted and moves upon headed pins h³ passing through the slot h⁴. A spring h² constantly tends to draw the studs into locking engagement with the wheels (see Fig. 6) 110 and the member K is lifted against the action of the spring to move the studs out of engagement with the wheels by a projection or shoulder a¹⁰ on the form plate A when the said plate is returning to and has almost reached its initial position (see Fig. 3). 115 Thus by the provision of this mechanism it is not possible to set the price printing roller to print one sum and then before the actual recording operation to reset the mechanism to record say a lower sum, as the locking 120 mechanism prevents any movement of the index unless and until it also moves the printing roller.

125 The two index mechanisms are so contrived that if the machine is operated either with or without a ticket, a ticket is added to the total as if really issued and some price also added to the money total to be accounted for.

130 The form plate A is reciprocated by the

lever D conveniently through a quadrant or segment D¹ connected to the shaft d of the operating handle or lever D, and gearing with a rack A³ on the plate A through a pinion B¹ on the impression roller B. In operation the operator sets the handles F and G to bring a particular type on the cylinders F¹ and G¹ flush with the printing surface of the plate A, a blank ticket is then inserted in the ticket slot of the casing and the lever D moved downward. The front end or edge of the ticket is gripped between the plate A and the roller B and is drawn into the machine, printed and ejected by the outlet slot. The impression roller B is conveniently of rubber and is situated from the front face of the plate a distance equal to about half the thickness of a ticket, so that the plate can perform its return journey without the matter thereon being printed off upon the surface of the roller B. The resiliency of the roller allows for the substance of the ticket or the roller may be mounted in yielding bearings. To provide a continuous surface for feeding the ticket the plate A is provided with ribs a¹¹.

Guides may be provided for directing the ticket through the machine but preferably the ticket which is not positively gripped while passing through the machine is bent by the pressure applied to it in passing between the form plate and impression roller and the delivery slot in the casing is positioned so that the ticket is automatically directed through it, thus it is only necessary for the user, before operating the controlling handle or lever, to insert the ticket far enough into the inlet slot for the front edge of the ticket to be gripped between the plate and roller.

The ink rollers E E¹ are rotated only by frictional contact with the matter on the form plate A and therefore to insure that the surface of the plate will be properly inked it is desirable that a relative movement takes place between the two contacting surfaces and preferably this is provided for by mounting the inking rollers upon split shafts e which can be expanded or contracted so that an adjustable or variable resistance to their rotation is provided.

Provision is made according to this invention to prevent the plate A being partially moved to print a ticket without recording its issue and the price at which it is issued. This is accomplished by mounting on the shaft d of the operating lever D, a toothed segment L¹ with which engages a spring-controlled pawl L so mounted as to allow the shaft to turn in one direction only until moved to the end of its travel. At both ends of this segment or rack is an offset L² which coincides with the limits of the travel of the plate A so that when the pawl enters one or other of these offsets it can be and is

automatically turned to lie in the opposite direction and allow the shaft to move in the opposite direction until the plate is moved to the other end of its travel.

In addition to the above described particulars, a dating mechanism J is provided on the form plate, where the same plate is to be used on various dates, the increments of the date being in the form of type capable of being set and locked in any well known manner. Likewise an automatically operated numbering mechanism H to number the tickets issued, consecutively is provided and the actuating arm H¹ thereof is operated automatically by the movements of the plate A.

The price printed on a ticket X is automatically registered and added up on a counter M the operations of which are controlled by the movement of the form plate A and the particular amount added is controlled by the price printing cylinder. Conveniently this is effected in the following manner: On one end the shaft of the cylinder F¹ is mounted a cam N or eccentric (see Figs. 3 and 5) adapted to engage one end of the actuating arm M¹ which is fulcrumed at m and carries a toothed quadrant m² controlled by a spring m¹ and gearing with a toothed wheel m³ on the main shaft of the counter M. When the plate A is moved down to effect the printing and issuing of a ticket the cam N engages and moves the said arm M¹ through a distance variable in accordance with the amount to be printed and recorded. The movement of the form plate also operates a counter O for adding up the total number of tickets issued. For this purpose the operating arm O¹ of the counter projects into the path of the plate A or it may be controlled by the movement of the lever D as by a stud or pin d¹ on the segment D¹. The arm O¹ is returned by a spring o.

The entire mechanism is inclosed in a locked or sealed casing P with the exception of the operating handle or lever and the index disks, the only openings being the slots e, e¹ for the insertion and removal of the tickets.

Although the invention has been described with reference to tickets having a series of stations or locations, designating symbols therefor and various prices, it is not to be limited thus as it may be employed for printing and issuing as required a series of like admission or other tickets, without designating symbols and with or without numbering these successively or dating them. In other words where tickets for admission to a building, inclosure or the like are required, and the price is the same for all tickets, the price printing device may be locked temporarily, or replaced by a fixed price printing mechanism, and similarly the

station or location printing device may be locked or omitted.

Having described my invention I declare that what I claim and desire to secure by Letters Patent is:—

1. In a machine for printing and issuing single or separate tickets, the combination of a reciprocating type carrying member, an impression member adapted to coöperate with the type carrying member, means for reciprocating the type carrying member, a casing inclosing said parts and having apertures for the admission of ticket blanks and the discharge of printed tickets arranged respectively at opposite sides of the impression member, the latter and the type carrying member being so related that a single movement thereof in one direction will feed a blank to printing position, print such blank, and deliver it as a printed ticket, and means for preventing retrograde movement of the type carrying member after a blank has been engaged thereby until said blank has been completely printed.
2. In a machine for printing and issuing single or separate tickets the combination with a fixed type carrying member movable in single plane, an impression member co-operating therewith to draw in, print, and deliver a ticket by a single or simple movement and means for moving the type carrying and impression members, of a movable type carrying member mounted on the fixed type carrying member, stationary means for adjusting the movable type carrying member, means for automatically connecting the adjusting means and type carrying member when the type carrying member is in one position only and means controlled by the type carrying member for automatically locking the adjusting means against operation when out of gear with the movable type carrying member.
3. In a machine for printing and issuing single tickets, the combination with a fixed type carrying member movable to and fro in a single plane, a movable type carrying member mounted to travel with the fixed type carrying member, an impression member coöoperating with the fixed type carrying member to draw in, print, and deliver a ticket by a single or simple movement, and means for moving the type carrying and impression members, of stationary means for adjusting the movable type carrying member, means for automatically connecting the adjusting means with the movable type carrying member, in one position only of the fixed type carrying member, means for automatically locking the type carrying member against return movement until a ticket has been printed, and means for automatically locking the adjusting means against operation when out of gear with the movable type carrying member.
4. In a machine for printing and issuing single or separate tickets, the combination of a casing provided with apertures adapted respectively for the admission of blanks to the printing devices and the discharge of printed tickets, a reciprocating type carrying member mounted within the casing, and provided with relatively fixed and adjustable type, or printing surfaces, an impression member within the casing adapted to co-operate with the type-carrying member so that a single movement of the latter in one direction will feed a blank, inserted through the proper opening in the casing, to printing position, print and deliver a complete ticket to the discharge opening, means for actuating the type-carrying and impression members, means for adjusting the adjustable type of the type-carrying member when said member is stationary at the limit of its movement in one direction, said means being rendered inoperative as the type carrying member moves from such position, and means insuring a complete reciprocation of the type carrying member at each actuation of the machine.
5. In a machine for printing and issuing single or separate tickets, the combination with a type carrying plate, guides in which the plate moves to and fro in a single plane, an impression roller, a handle, gearing between the handle the plate and the roller, a type drum mounted on the plate, an adjusting handle therefor, a gear wheel on the drum a gear wheel on the handle and adapted to engage the drum gear wheel in one position only of the plate, a spring controlled catch, and means on the plate for disengaging said catch from the handle gear wheel.
6. In a machine for printing and issuing single tickets the combination with a type carrying plate, guides in which the plate moves to and fro in a single plane, an impression and feeding roller, a plurality of movable type carrying drums rotatably mounted on the plate, an adjusting handle for each drum, rotatably mounted on the machine casing, a gear wheel on each drum, a gear wheel on each handle and adapted to engage the drum gear wheels when the plate is in a particular position, a spring controlled pawl engaging each handle gear wheel, means on the plate for disengaging the pawls from the wheels.
7. In a machine for printing and issuing single or separate tickets, the combination with a flat type carrying plate, guides in which the plate moves to and fro in a single plane, two rotatable type carrying drums mounted in the plate, an adjusting handle for each drum mounted in the casing, a gear wheel on each drum, a gear wheel on each handle, the said gear wheels only gearing when the plate is in position for a ticket to

be inserted, a spring controlled pawl engaging each handle gear wheel, projections on the plate adapted to disengage the pawls from the gear wheels, a cam on one of the drums, a dating and printing device on the plate and two inking rollers each adapted to ink a separated part of the plate.

In testimony whereof I have signed my name to this specification in the presence of two subscribing witnesses.

ALFRED JAMES JUNG.
